UNITED STATES PATENT OFFICE.

AUGUST CARLEWITZ, OF NEWARK, NEW JERSEY.

DESIGN FOR A CORNICE.

SPECIFICATION forming part of Design No. 21,580, dated May 24, 1892.

Application filed April 2, 1892. Serial No. 427,568. Term of patent 7 years.

To all whom it may concern:

Be it known that I, AUGUST CARLEWITZ, a citizen of the United States, residing at the city of Newark, in the county of Essex and

5 State of New Jersey, have invented and produced a new and original Design for a Cornice, to be used in the angle formed by the wall and ceiling of a room, of which the following is a specification, reference being had to 10 the accompanying drawings, showing a part thereof.

The drawings show one section of the entire cornice, the opposite ends being designed to match, the completed cornice being made 15 up of such sections.

Figure 1 is a front elevation of the cornice, showing my design complete. Fig. 2 is a cross-section through the line *aa* of the same.

20 The prominent feature of my design consists in a raised figured surface, the outlines

of which when viewed in elevation, as in Fig. 1, will lie principally within the cove of the cornice, but also extending over the upper and lower beads thereof.

A is the cove of the cornice, which is concave in form, and B C are respectively the upper and lower beads or moldings.

The central feature of the design consists of a bunch of flowers, leaves, and seed-pods D, tied at the base or stems by a ribbon E, 30 which extends laterally on both sides of the bunch of flowers along the cove.

What I claim is—

The design for a cornice, herein shown and described.

AUGUST CARLEWITZ.
